US00D993214S

(12) **United States Design Patent** (10) **Patent No.:** **US D993,214 S**
(45) **Date of Patent:** **** Jul. 25, 2023**

(54) **AUDIO HEADSET WITH MICROPHONE**

(71) Applicant: **Beyerdynamic GmbH & Co. KG**,
Heilbronn (DE)

(72) Inventor: **Eduardo Ponzoni**, Stuttgart (DE)

(73) Assignee: **BEYERDYNAMIC GMBH & CO.**
KG, Heilbronn (DE)

(**) Term: **15 Years**

(21) Appl. No.: **35/514,284**

(22) Filed: **Apr. 25, 2022**

(80) **Hague Agreement Data**

Int. Filing Date: **Apr. 25, 2022**

Int. Reg. No.: **DM/220606**

Int. Reg. Date: **Apr. 25, 2022**

Int. Reg. Pub. Date: **May 13, 2022**

(30) **Foreign Application Priority Data**

Oct. 27, 2021 (EM) 008739874-0001
Oct. 27, 2021 (EM) 008739874-0002

(51) **LOC (14) Cl.** **14-01**

(52) **U.S. Cl.**

USPC **D14/206**; D14/226

(58) **Field of Classification Search**

USPC D14/206, 205, 226; D29/112; 2/209;
381/380-381, 374, 378; 362/105
CPC H04R 25/00; H04R 25/02; H04R 1/1066;

Primary Examiner — Paula Allen Greene

(74) Attorney, Agent, or Firm — Fross, Zelnick, Lehrman & Zissu, PC; Charles T.J. Weigell, Esq.

(57) **CLAIM**

The ornamental design for an audio headset with microphone, as shown and described.

DESCRIPTION

- 1.1 Left
- 1.2 Right
- 1.3 Perspective
- 1.4 Partial enlarged view
- 1.5 Front
- 1.6 Top
- 1.7 Partial enlarged view
- 2.1 Left
- 2.2 Right
- 2.3 Perspective
- 2.4 Partial enlarged view
- 2.5 Front
- 2.6 Top
- 2.7 Partial enlarged view

Views 1.4 and 1.7 are partial enlarged views of 1.1 and 2.4 and 2.7 are partial enlarged views of 2.1.

1 Claim, 14 Drawing Sheets
